UNITED STATES PATENT OFFICE.

LESTER GUY COOK, OF LINCOLN, NEBRASKA.

PORCH AND LAWN SWING.

Application filed February 1, 1927. Serial No. 165,137.

My invention relates to wheel supported swings and my primary object is the provision of a light weight portable swing of small size, having only one seat in the place of the usual two seats facing each other.

Another object of my invention is the provision of a swing which is specially adapted to be used on porches and particularly on the porches of small size.

Another object is the provision of structural features whereby the swing is made as safe as it is possible for such a swing to be, so that there can be no danger of the tipping of the swing nor danger of injury to the limbs or fingers of children or careless persons.

Still another of my objects is the provision of features whereby both sides of the swing are moved positively and in unison to thus add materially to the comfort of the occupants and to the life of the swing.

Having in view these objects and others which will be pointed out in the following description, I will now refer to the drawings, in which

Figure 1 is an end view of the swing, the covering being removed to disclose interior parts.

Figure 2 is a view in perspective of the supporting structure for the tracks.

Figure 3 is an illustration of a portion of the seat and of one of its supports.

Figure 4 is a view in perspective of one of the end portions of the carriage on which the seat frame rides.

Figure 5 is a view partly in front elevation and partly in section of the right-hand end portion of the swing.

The framework of the swing including the support for the tracks is partly shown in Figure 2, this figure showing only the right-hand portion which is duplicated at the opposite end of the frame. It consists of two longitudinal beams 10 and 11 connected together by means of uprights 12, 13 and 14.

The beam 10 projects beyond the uprights 12 and 14 and is braced thereto by means of the braces 15. The upright 13 projects above the beam 11 and is provided at its upper end with a stop 16, the function of which will be described in connection with the description of the operation of the swing.

The frame shown in Figure 2 is, of course, duplicated on the left-hand side of the swing and the two parts are rigidly secured together by means of the horizontal beams 17

which are braced to the end portions of the swing by means of the braces 18. The frame includes also arcuate tracks 19, 20 and 21, the tracks 19 and 20 being designed to support the seat and the track 21 being designed to support the footrest. The two tracks 21 at opposite ends of the swing are secured together by means of the beams 22. All of the tracks are secured to the frame by means of spacers 23 which space the tracks from the frame. The three tracks are arcuate in form, the arcs being substantially alike. The tracks 19 and 21 are smooth but the track 20 is provided with a rack 24 on its inner surface. It is my object to construct the frame largely of wood but the rack 24 is preferably made from a suitable metal such as iron or steel.

The carriage is best shown in Figures 1 and 4. It consists of two horizontal beams 25 supporting flanged rollers 26 and 27 between them. Depending from the beams 25 is a beam 28 which is securely braced to the beams 25 by means of the braces 29. At the lower end of the upright 28 there is secured a platform 30 by means of a pivot 31. This platform has a depending member 32 carrying at its lower extremity a flanged wheel 33 which is considerably smaller in diameter than the wheels 26 and 27. The opposite end members of the carriage, of which only the right-hand end member is shown, are rigidly secured together by means of the beam 34, and the shaft 35 unites the two wheels 27 in rigid relation. Likewise the platform includes floor members 36 connecting the two end members and braced thereto as shown. The flanges of the wheels 26 and 32 are smooth but the flanges of the wheel 27 are toothed. The toothed inner flange of the wheel 27 is designed to coat with the rack 24.

The seat comprises an ordinary bench seat 37 having end members 38 as shown in Figure 3. Secured to the members 38 are inverted tracks 39 and 40, these also being spaced by means of spacers 41. The tracks 39 and 40 are arcuate in form, the arcs being substantially identical with each other and with the arcs of the tracks 19, 20 and 21. The track 40 is provided with a rack 42 which is similar to the rack 24 of the track 20. The rack 42 is designed to cooperate with the outer toothed flange of the wheel 27 whereas the rack 24 is adapted to cooperate with the inner toothed flange of the wheel

27. When the parts are in position, the wheels 26 and 27 rest on the tracks 19 and 20 with their flanges overlying the edges of the tracks and with a meshing of the inner 5 flange of the wheel 27 with the rack 24. At the same time the tracks 39 and 40 will bear against the upper surfaces of the wheels 26 and 27, the flanges of which prevent the seat from jumping the track.

10 The bar 39 of the seat frame has its upper edge formed as shown in Figures 1 and 3. As the seat moves toward one end or the other of its stroke it rises slightly and the bar 39 is also similarly elevated. As the 15 seat approaches the limit of its movement the weight of the occupant will slightly unbalance the seat so that the seat has a tendency to tip. The stop 16 is immediately above the upper surface of the bar 39 but 20 it does not contact with the upper surface during the main portion of the stroke of the seat. At the time when the seat becomes more or less balanced over a pair of the 25 wheels or rollers 26 and 27, one of the upper projections 39' of the upper edge of the bar 39 engages the stop 16 which permits the seat to continue its stroke but which prevents any tilting. The limit of the stroke is, of course, defined by the stops at the 30 ends of the bar 39 as shown in Figures 1 and 3. When either of these two stops engages the stop 16 the limit of movement has been reached, since these two stops are designed to positively engage the stop 16 at 35 the limit of movement of the swing.

In order to prevent any accidents to children or others, the working parts of the swing are covered. A wall 43 is provided at the sides as shown in Figure 5 so as to make 40 the tracks and rollers inaccessible. The top is also covered with a top wall 44, this top wall being secured to the seat frame to move therewith.

One of the primary objects of the invention 45 has been to make the swing as safe as it is possible to make such a swing. This has been accomplished and largely by means of the stop arrangements which prevent any tilting of the seat when the seat is in 50 either its extreme forward or in its extreme rearward position. The pinions 27 which

are secured to the shaft 35 are also instrumental in increasing the safety of the swing. When the weight on the seat is not evenly distributed, as when it is occupied by only one person sitting at one end of the bench, a torsional effect is produced and the swing then has a slight tendency to turn on its vertical axis. The result of this might, of course, be that the seat left its tracks to the 60 injury of the occupant and the damage of the swing. The pinions, however, hold the parts against turning movements about a vertical axis and the flanges on the rollers have a similar effect. The shaft 35 forces the pinions 27 to move in unison and to thus reduce the tendency toward any torsional movement of the swing.

The seat member moves at a rate which is 70 about twice that of the movement of the foot platform. This makes it an easy matter to actuate the swing by pressing forwardly with the feet on the foot platform. The entire swing, having but one bench, is easily placed on the porches of small size which 75 are so popular at the present time.

Having thus described my invention in such full, clear, and exact terms that its construction and operation will be readily understood by others skilled in the art to 80 which it pertains, what I claim as new and desire to secure by Letters Patent of the United States is:

A porch swing including a frame having 85 a pair of arcuate racks at the sides thereof and having a pair of arcuate tracks forward of said arcuate racks and having also a pair of arcuate tracks below and forward of said first named tracks, a seat member having a rear shaft provided with a pair of pinions 90 secured thereto for traveling on said arcuate racks, a pair of wheels supporting the forward portion of said seat member and adapted to travel in said first named tracks, a foot rest platform pivotally secured at the 95 rear extremity thereof to said seat member, and a pair of wheels for traveling in said second named arcuate tracks and supporting the forward portion of said foot rest platform.

In testimony whereof I affix my signature.
LESTER GUY COOK.
